RAILWAY AXLE JOURNAL LUBRICATOR

James J. Hennessy, Chambersburg, Pa., assignor
to Hennessy Lubricator Company, Inc., Chambersburg, Pa., a corporation of Delaware

Application December 21, 1950, Serial No. 202,006

11 Claims. (Cl. 308—84)

1 The invention relates to the pumping of lubricant from the bottom of a railway journal box to the journal as is described generally in Patent 1,948,297, issued to me February 20, 1934, and more particularly to the operation of a collapsible body pump by the play of the axle journal crosswise of the journal box as shown in my copending application, Serial No. 131,579, filed December 7, 1949, now Patent No. 2,639,200. The invention comprises novel pump structure and actuating mechanism therefor, particularly well adapted for use in journal boxes of American Association of Railroads type in which the space between the journal and the bottom of the box is so restricted that it is difficult to insert, remove, or operate a pump as shown in the above-mentioned patent or application.

The main object of the invention is to provide a simple, effective pump which requires little vertical space for operation. A more specific object is to effect pumping action by alternately reducing and increasing the volume of a flexible pump chamber other than by direct movement of the ends of the chamber towards and away from each other as shown in the copending application referred to above. This may be done by twisting and untwisting the pump body about its longitudinal axis or by compressing the pump laterally of its ends.

In the accompanying drawings illustrating selected embodiments of the invention:

Figure 1 is a vertical longitudinal section through a railway axle box showing the journal on which the box is mounted and the essential parts of the lubricator including the novel pump structure.

Figure 2 is a top view of the pump and pump operating structure and is drawn to an enlarged scale.

Figures 3 and 4 are vertical detailed sections taken on the lines 3—3 and 4—4 respectively of Figure 2.

Figure 5 is a section corresponding to Figure 1 but showing another form of the invention.

Figure 6 is in part a front view of the pump and in part a vertical transverse section on the line 6—6 of Figure 5.

Figure 7 is a top view of the pump and associate parts shown in Figure 5.

The journal box 1 is mounted on the journal 2 by the usual bearing 3 and wedge 4. A lubricant distributor 5 in the form of an arcuate pad and support plate is applied to the lower face of the journal and is held against the journal by a jointed support comprising frames 6 and 7

with adjacent ends pivoted to each other at 8. The outer end of frame 6 bears against the lower inner corner of the box and the outer frame 7 is curved to contact the upwardly and forwardly extending wall 9 of the box and to mount a yielding yoke 9 engaging a downwardly facing element 10a of the box top wall 10. This type of distributor support is disclosed and claimed in my copending application, Serial No. 167,709, filed June 10, 1950. Downward thrust by yoke springs 11 on the outer ends of frame 7 thrusts the distributor upwardly against the journal.

A base 12 has ears 13 hooked over frame 7 and the inner end of base 12 mounts a retainer 14 forming with base 12 a channel-like recess 15 extending horizontally in an arc approximately 270 degrees about the upright axis A of the pump.

The pump comprises a chamber 16, preferably of cylindrical shape, the sides being formed of flexible material, such as leather, preferably with folds and creases extending lengthwise of the chamber. The pump chamber has a bottom wall 17 apertured at 18 and provided with an inlet check valve 19 comprising a disc loosely held in position by crossed staples 20. The upper end of the pump has a top wall 21 provided with a similar outlet check valve 22 leading to an opening 23 in distributor 5.

Chamber lower wall 17 is secured to a horizontal ring 24 having a flange 25 freely received in recess 15 and provided with an extension 26 projecting laterally of the pump chamber between the spaced ends of retainer 14.

The forward portion of base 12 mounts a lever fulcrumed at 27 and having an arm 28 with a pin and slot connection 29 to extension 26 of ring 24. The other arm 30 of the lever has a pivotal connection at 31 to a contact rod 32, the upper end of which is equipped with a head 33 engaging the outer end of journal 2.

As the journal plays crosswise of the box and moves to the left from the position shown in Figure 1, rod 32 will swing lever 28, 30 from the full line position shown in Figure 2 to the broken line position and this movement of the lever will twist the wall of pump chamber 16 about axis A, as indicated in Figure 1, thereby decreasing its volume and causing lubricant in the chamber to be discharged through valve 22 to the distributor. When journal 2 moves to the right, a spring 34 will return lever 28, 30 to its original position untwisting the wall of pump chamber 16, increasing the volume of the chamber and resulting in the closure of valve 22, the opening of valve 19

and the intake of lubricant from the lower portion of the journal box into the pump chamber.

Pump chamber 16 functions as a pump and at the same time constitutes a conduit leading from the lowermost portion of the box, which is a lubricant sump or reservoir, to the journal.

As the journal plays back and forth in the box, there will be a series of twistings and untwistings of the pump chamber wall, with intermittent intakes and discharges of lubricant, maintaining a constant supply of lubricant to the distributor and journal.

The pump is simple to construct and to install in an ordinary A. A. R. journal box and is readily received and operated in an application where the distance between the journal and the bottom of the box is as little as one and one-half inches which is about half of the normal clearance between the journal and the bottom of the box.

By varying the relation between the lever arms 28, 30, the amount of twisting of the pump chamber wall may be controlled as may be required to meet the amount of play of the journal in the box and other operating conditions.

In the arrangements shown in Figures 5, 6, and 7, the journal, bearing, wedge, and box are substantially the same as previously described, but the distributor 40 is supported from the box bottom wall by coil springs 41. The pump, and distributor, are spaced longitudinally of the box by a rod-like retainer 42 and a plate 43, secured at one edge to the left hand end of the retainer by weld W and having its edges flanged downwardly as at 44 and preferably welded to the box at W'.

The pump actuating mechanism comprises a support block 45 seated on the box bottom wall and fitting within an opening in plate 43. A lever 46 is pivoted at 47 on block 45 and the upper end of the lever bears against the end of the journal and is moved to the left of the box as the journal moves between the full line and broken line positions. A plunger 48 slides horizontally in a bearing 49 therefor in block 45 and the left hand end of the plunger has a pin 50, received in a slot 51 in the lower end of lever 46.

The pump body 52 comprises a chamber, substantially rectangular in cross section and elongated transversely of the box. The lower and upper walls 53, 54, respectively, of pump body are apertured for the admission and discharge of lubricant and the apertures are fitted with flap valves providing for admission of lubricant from the bottom of the box through bottom wall 53 when the pump chamber is expanded and for discharge of lubricant through the top wall 54 when the chamber is reduced in volume.

To effect the change in volume of the chamber, one wall 55 is formed of leather or like material and of sufficient area to be bulged outwardly of the chamber, as shown in Figure 1, or to be moved inwardly of the chamber as lever 46 and plunger 48 are shifted by the play of the journal in the box. The pump inner wall 56 is relatively rigid and is backed up by a clip 57, secured to retainer 42. A spring 58 is compressed between walls 55 and 56 and tends to bulge wall 56 outwardly and return plunger 48 and lever 46 to the position shown in Figure 1 whenever the journal moves to the right.

Wall 56 may have some flexibility and the pump body top and bottom walls may be thrust apart by a spring 59 to accommodate variation in the distance between the box bottom wall and the distributor and journal. Preferably, a coil spring

60 bears against each valve on the pump top wall and avoids flow of lubricant downwardly from the distributor, irrespective of the action of plunger 48 and spring 58.

5 By changing the length of the pump body, the capacity of the pump may be varied to meet different conditions. The curvature of the bottom wall of the pump and the provision of clips near the ends of this wall, and at a higher level than the aperture near the middle of the wall, will enable lubricant to flow into the pump, even though there is an accumulation of water in the bottom of the box from moisture condensation or from box leakage.

10 15 With this arrangement there is less crimping or less creasing of the leather than in the arrangement previously described and, as indicated above, the capacity of the pump may be changed readily, by varying the length of the pump chamber, without varying the lever stroke.

20 The details of the structures may be varied otherwise than as described about without departing from the spirit of the invention and the exclusive use of those modifications coming 25 within the scope of the claims is contemplated.

What is claimed is:

1. In a railway axle journal lubricator, a lubricant distributor for application to the underside of a journal, a base spaced below said distributor, 30 a chamber having walls of flexible material with folds extending lengthwise and extending from said base to said distributor, intake and outlet check valves in the lower and upper portions respectively of said chamber, a member associated 35 with the lower portion of the chamber and movable to twist the chamber about its axis to reduce its volume, and a device extending upwardly from said member and having a part facing towards said distributor but spaced therefrom and operable by contact with a journal shifting lengthwise of the distributor to accommodate said member.

40 2. In a railway axle journal lubricator, a lubricant distributor for application to a journal, a base below said distributor and spaced therefrom, a member rotatable on said base about an upright axis, a conduit of flexible material with its upper end secured to said distributor and its lower end secured to said member, inlet and 45 outlet check valves in the upper and lower portions, respectively, of said conduit, a horizontally disposed lever having an upright pivot on said base and an arm operatively connected to said member and an actuating arm, there being a device extending upwardly from said actuating arm and having a part facing towards but spaced from said distributor for contact with the end of a journal to which the distributor is applied.

3. In combination with a railway axle journal 50 and a box mounted thereon, a lubricant distributor applied to the bottom of the journal, a support for said distributor mounted on the bottom of the box, an elongated chamber of leather-like material depending by its upper end from the distributor, inlet and outlet check valves in the lower and upper portions of said chamber, respectively, an operating member movably mounted in the box and having a part opposing the end of the journal, a device movable horizontally 55 and operatively attached to the lower portion of said chamber during such movement, and an operative connection between said member and said device.

60 70 75 4. In combination with a railway axle journal and a box mounted thereon, a lubricant distribu-

tor applied to the bottom of the journal, a supporting frame for said distributor mounted on the bottom of the box, a chamber of leather-like material depending from the distributor, inlet and outlet check valves in the lower and upper portions of said chamber, respectively, an operating member movably mounted in the box and having a part opposing the end of the journal, a lateral extension on the lower portion of said chamber, and a lever pivoted on said frame with one arm connected to said operating member, and the other arm connected to said extension.

5. In a railway axle journal lubricator, a base, a retainer cooperating with said base to form an arcuate recess exceeding 180°, a disc-like member rotatable in said recess, a cylinder of leather-like material having its lower end closed by said member, a disc-like member closing the upper end of said cylinder, inlet and outlet check valves in said lower and upper members, respectively, a device for rotating the lower member while the upper member is held against rotation, whereby the chamber is twisted and untwisted and its volume is decreased and increased alternately.

6. In a railway axle journal lubricator, a support structure, a lever fulcrumed on said structure with one arm extending upwardly therefrom and disposed to engage the end of a journal to which the lubricator may be applied, a pumping device associated with said structure and including a chamber having a flexible side wall and a spring thrusting said wall outwardly of the chamber, there being check valves leading into and out of said chamber, and an operative connection between said lever and said wall for moving the latter inwardly of the chamber against the thrust of said spring.

7. In a railway axle journal lubricator, a support structure, a pumping device associated with said structure and including a collapsible chamber, one side wall of which is backed by a portion of said structure and the opposite side wall of which may flex inwardly and outwardly of said chamber, a lever fulcrumed on said structure with one arm disposed to engage a portion of a journal to which the journal may be applied, a member operable by another arm of said lever for moving said flexible wall inwardly of the pump chamber, and a spring compressed between said walls.

8. In a railway axle journal lubricator, a support structure, a lever fulcrumed on said structure with one arm extending upwardly from the support structure and disposed to engage an end portion of a journal to which the lubricator may be applied, a horizontal reciprocating member operable by another arm of said lever, and a pumping device associated with said structure and including a chamber having a flexible side wall and yielding means opposing said member, there being inlet and discharge check valves in said chamber.

9. In a railway axle journal lubricator, a support structure, an upright lever fulcrumed on said structure with its upper arm disposed to engage the end of a journal to which the lubricator is applied, and a pumping device associated with said structure and having a flexible side wall, a member movable horizontally by a thrust from said lever to distort said wall as said lever is moved in one direction about its fulcrum, and means for returning said wall to normal position and moving said lever in the opposite direction about its fulcrum when said lever thrust is released.

10. In a railway axle journal lubricator, a pump including a chamber with a flexible upright wall, there being inlet and outlet check valves at the bottom and top of said chamber respectively, a device associated with the pump and movable in a direction transversely of the axis of said chamber for distorting said wall inwardly of said chamber, and structure operably connected to said device and having a part for engaging an end portion of a journal to which the lubricator is applied to be actuated thereby.

11. In a railway axle journal lubricator, an elongated lubricant distributor having an upwardly facing surface concaved transversely of its length for application to the underside of a journal to be lubricated, an elongated conduit of flexible material depending from said distributor, intake and outlet check valves in said conduit spaced substantially from each other vertically, the lower end of said conduit being rotatable about the longitudinal axis of the conduit and relative to the upper end of the conduit, a member reciprocable lengthwise of said distributor and connected to the lower end of said conduit for alternately twisting said conduit about its longitudinal axis to reduce and increase its volume, and a device operatively connected to said member and having an element above the level of said distributor and facing towards but spaced from one end of said distributor so as to engage the end of a journal to which the distributor is applied.
